US0D1107791S

(12) United States Design Patent (10) Patent No.: US D1,107,791 S
 Meraz et al. (45) Date of Patent:  Dec. 30, 2025

(54) PAYMENT CARD WITH A BOX

- (71) Applicant: Visa International Service Association, San Francisco, CA (US)
- (72) Inventors: Salvador Timothy Meraz, Santa Ana, CA (US); Amelia Rose Stier, Inglewood, CA (US)
- (73) Assignee: Visa International Service Association, San Francisco, CA (US)
- () Term: 15 Years
- (21) Appl. No.: 29/875,964
- (22) Filed: May 12, 2023

Related U.S. Application Data

(62) Division of application No. 29/801,418, filed on Jul. 28, 2021, now Pat. No. Des. 992,022, which is a division of application No. 29/669,085, filed on Nov. 5, 2018, now Pat. No. Des. 929,499.

CLAIM

The ornamental design for a payment card with a box, as shown and described.

DESCRIPTION

FIG. 1 is a back side perspective view of a first embodiment of a payment card with a box showing our new design.
FIG. 2 is a back side view thereof.
FIG. 3 is a front side view thereof.
FIG. 4 is a top elevational view thereof.
FIG. 5 is a bottom elevational view thereof.
FIG. 6 is a left side elevational view thereof.
FIG. 7 is a right side elevational view thereof.
FIG. 8 is a back side perspective view of a second embodiment of a payment card with a box showing our new design.
FIG. 9 is a back side view thereof.
FIG. 10 is a front side view thereof.
FIG. 11 is a top elevational view thereof.
FIG. 12 is a bottom elevational view thereof.

FIG. 13 is a left side elevational view thereof.
FIG. 14 is a right side elevational view thereof.
FIG. 15 is a back side perspective view of a third embodiment of a payment card with a box showing our new design.
FIG. 16 is a back side view thereof.
FIG. 17 is a front side view thereof.
FIG. 18 is a top elevational view thereof.
FIG. 19 is a bottom elevational view thereof.
FIG. 20 is a left side elevational view thereof.
FIG. 21 is a right side elevational view thereof.
FIG. 22 is a back side perspective view of a fourth embodiment of a payment card with a box showing our new design.
FIG. 23 is a back side view thereof.
FIG. 24 is a front side view thereof.
FIG. 25 is a top elevational view thereof.
FIG. 26 is a bottom elevational view thereof.
FIG. 27 is a left side elevational view thereof; and,
FIG. 28 is a right side elevational view thereof.
The broken lines showing the account identifier numbers, integrated circuit, cardholder name, signature box, expiration date, and security code are included for the purpose of illustrating environmental structure and form no part of the claimed design.
